UNITED STATES PATENT OFFICE.

ALFRED J. ANDERSON, OF WYLIE, MINNESOTA, ASSIGNOR OF ONE-HALF
TO P. A. EKSTROM, OF WYLIE, MINNESOTA.

CHURN.

No. 806,616.

Specification of Letters Patent.

Patented Dec. 5, 1905.

Application filed June 1, 1905. Serial No. 263,278.

To all whom it may concern:

Be it known that I, ALFRED J. ANDERSON, a citizen of the United States, residing at Wylie, in the county of Red Lake, State of Minnesota, have invented certain new and useful Improvements in Churns; and I do hereby declare the following to be a full, clear, and exact description of the invention, such as will enable others skilled in the art to which it appertains to make and use the same.

This invention relates to churns.

The principal object of the invention resides in the provision of a simple, inexpensive, durable, and efficient device of the character named for churning purposes.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made within the scope of the claim without departing from the spirit or sacrificing any of the advantages of the present invention.

In the accompanying drawings, Figure 1 is a vertical sectional view illustrating my invention. Fig. 2 is a detail perspective view of one of the elements forming two dashers of a set of the latter. Fig. 3 is a top plan view of one set of dashers.

Referring now more particularly to the accompanying drawings, the reference character 1 designates the body of the churn, having a journal-bearing 2 arranged centrally and upon the inner surface of its bottom for the reception of the lower end of the dasher-shaft 3, whose upper end passes through a bushing 4 in the cover 5 and is fixedly secured to the latter in any suitable manner, there being a pinion secured to the bushing 4 and arranged for rotation upon the outer face of the cover 5. It will be seen that the upper end of the bushing has a laterally-directed flange 6, between which and the upper surface of the cover 5 the pinion rotates in a manner to be hereinafter fully explained.

Fixedly secured upon the top of the cover 5 is a V-shaped bracket 7, having alining perforations 8 for the reception of a revoluble shaft 9, provided at its free end with a crank-

wheel 10 and having a gear-wheel 11 fixedly secured to its opposite end for mesh with the pinion 6 of the dasher-shaft 3.

From the foregoing it will be readily seen that by grasping the handle 12 of the crank-wheel 10 the shaft 9 will rotate the gear-wheel 11, which is in mesh with the pinion 6, to rotate the dasher-shaft 3, and reference to the drawings will disclose that this shaft is provided with a series of shoulders 13, 14, and 15, resulting in the formation of a dasher-shaft of greater cross-sectional diameter in steps toward its lower end.

Four dashers are arranged upon each shoulder 13, 14, and 15, the dashers being of peculiar formation. In other words, two elements compose the four dashers, the said elements crossing each other at their point of intersection with the dasher-shaft. It will be seen that one of these elements 16 has its opposite ends enlarged, forming the oppositely-disposed dasher-blades 17, provided with perforations 18, the said blades being bent at a direct right angle to the plane of the intermediate portion 19 of the member from which they are formed, the said intermediate portion 19 being provided with a rectangular opening 20, whereby the element of which the blades are formed may be fitted upon the shaft, which latter is preferably rectangular in cross-section. It will be seen, too, that the intermediate portions of each element forming the blades cross each other, resulting in one being disposed directly upon the other at their reduced intermediate portions. These elements or dashers comprise one set, and it will be understood that there is a set of dashers, such as those described, disposed upon each of the shoulders 13, 14, and 15. If desired, a small pin or other suitable element 21 may pierce the dasher-shaft immediately above the other element forming the dashers, so as to prevent longitudinal movement of the latter along the shaft. Of course the trunnion 22 at the lower end of the dasher-shaft 3 is arranged centrally of the latter and is of just sufficient length to hold the lower end face of the dasher immediately above the journal-bearing 2.

By reason of my peculiar formation of dashers the cream is turned upwardly through centrifugal force, causing a rapid progress in

the churning of the butter, and reference to the drawings will disclose that if I desire I may dispose a small faucet 23 in the bottom of the churn-body 1 for the purpose of extracting or withdrawing buttermilk from the churn during the churning operation.

It will now be understood from the manner in which I state that the dasher-shaft is operated that the respective sets of dashers fit tightly upon the shaft in engagement with the corresponding shoulders of the latter, and when it is desired to remove the dashers and their shafts from the interior of the body 1 it is simply necessary to lift the cover 5 from the top of the body, when, by reason of the dasher-shaft being fixedly secured to the bushing of the cover and upon which the faucet-pinion is mounted, the shaft may be

readily disengaged from its bearing 2 and easily removed from the body for churning purposes.

What is claimed is—

In a churn, a body, a dasher-shaft journaled in said body, the shaft having a series of enlargements to form shoulders arranged 25 one above the other, dashers arranged upon the shaft and supported by the said shoulders, means for operating the shaft and its dashers, and an outlet at the bottom.

In testimony whereof I affix my signature 30 in presence of two witnesses.

ALFRED J. ANDERSON
